UNITED STATES PATENT OFFICE.

JOSEPH BARRETT, OF NEW YORK, N. Y., ASSIGNOR TO AMERICAN LINOLEUM MANUFACTURING COMPANY, OF SAME PLACE.

DESIGN FOR FLOOR-CLOTH.

Specification forming part of Design No. **7,848**, dated November 10, 1874; application filed October 10, 1874.
[Term of Patent 3½ years.]

To all whom it may concern:

Be it known that I, JOSEPH BARRETT, of the city, county, and State of New York, have invented a Design for Linoleum Floor-Cloth, of which the following is a specification:

The nature of my design is fully represented in the accompanying photographic illustration, to which reference is made.

A represents a diamond border, that connects at the corners with the adjoining parts of the floor-cloth. It incloses a smaller square band, B, the corners of which are placed midway between the sides of the outer border or band, and which is provided on a darker background with a continuous geometric ornamentation in lighter colors. The triangular

spaces formed by the inner and outer squares are filled up with figures corresponding in shape thereto. A rosette, C, with fringed and forked leaf-shaped parts, extending from the circular center diagonally toward the corners of the inner square, is placed centrally in lighter colors on the dark ground of the inner square.

I claim as my invention —

The design for a floor-cloth, as shown and described.

JOSEPH BARRETT.
